UNITED STATES PATENT OFFICE.

MILTON H. SHOENBERG, OF SAN FRANCISCO, CALIFORNIA, ASSIGNOR TO MAJESTIC ELECTRIC DEVELOPMENT CO., OF SAN FRANCISCO, CALIFORNIA.

DESIGN FOR A RADIANT ELECTRIC HEATING UNIT.

59,133.

Specification for Design. Patented Sept. 20, 1921.

Application filed February 26, 1920. Serial No. 361,561. Term of patent 14 years.

To all whom it may concern:

Be it known that I, MILTON H. SHOENBERG, a citizen of the United States, and a resident of the city and county of San Francisco, State of California, have invented a new, original, and ornamental Design for a Radiant Electric Heating Unit, of which the following is a specification, reference being had to the accompanying drawings, forming a part thereof.

Figure 1 is a perspective view of my heat unit.

Fig. 2 is a cross section of Fig. 1 on the line II—II thereof.

I claim:

The ornamental design of a radiant electric heating unit substantially as shown.

MILTON H. SHOENBERG.
